UNITED STATES PATENT OFFICE.

RICHARD M. STEPHENS, OF GLEN ELLEN, CALIFORNIA, ASSIGNOR, BY MESNE ASSIGNMENTS, OF ONE-HALF TO ELMER L. LIPP AND CHARLES E. MANLEY, AND ONE-HALF TO CHARLES F. DEGNER, ALL OF LOS ANGELES, CALIFORNIA.

WATER-HEATER.

1,366,752

Specification of Letters Patent. Patented Jan. 25, 1921.

Application filed December 27, 1919. Serial No. 347,819.

To all whom it may concern:

Be it known that I, RICHARD M. STEPHENS, of Glen Ellen, California, have invented certain new and useful Improvements in 5 Water-Heaters, whereof the following is a specification.

This invention relates to electric water heaters, and is intended to heat small bodies of water, such as a cupful, or a small pailful, 10 &c. The object of the invention is to produce such a heater which shall be cheap to construct, and durable and effective in use.

The invention comprises a heating member composed of an outer protective shell, 15 with a cap and handle at one end thereof, and within the outer shell, a hollow cylinder of chemically inert material, and preferably of low electric conductivity, such as graphitic carbon, and within this hollow cylinder, a second hollow cylinder of similar material. Both carbon cylinders and the outer protective shell are perforated at intervals 20 to permit the circulation of water through and about them, and the inner carbon cylinder is open at the bottom for the same purpose. The two carbon cylinders are connected with the two poles of an electric circuit, so that when the instrument is plunged 25 into water, a current will flow, and the water which circulated through the instrument 30 will be heated.

I have fully illustrated the instrument in the accompanying one sheet of drawing, in which;

35 The figure shows the instrument in elevation, the lower part being in section to show the interior.

Referring to the drawing, 1 represents the outer, or protective shell, which may be 40 made of tin, or any other material which it is convenient to use. This outer shell is perforated at intervals with holes 2, opening into its interior. Inside the shell 1 is a carbon shell or hollow cylinder 3, which is 45 also pierced with holes 4, opening into its interior. Within the cylinder 3, is a second hollow cylinder 5, also pierced with holes 6, opening into its interior. The two cylinders are spaced from each other, and from the 50 outer shell, by rings 11 of rubber or other non-conducting material. The bottom of the inner carbon cylinder is open. The cylinders 3 and 5 are connected at the top with the

two strands of a lamp cord, or other electric conductor, as seen at 10. Current thus 55 flows through the cord, which may be provided with an ordinary lamp plug, and be screwed into an ordinary lamp circuit, and through the carbon cylinders, and the water between them, and thus heats the water, 60 when the instrument is plunged thereinto, the water circulating through and about the cylinders through the holes 2 and 4 and the open bottom of the cylinder 5. The cords 10, and their connections with the cylinders, 65 are thoroughly protected by the cap 7 and the handle 9, from the water into which the instrument is plunged. The cap may be secured to shell 1 by a screw, as 8, or in any other way, or may be made integral therewith. The user of the instrument may thus 70 use it without wetting the hands, or getting them into the water, a particularly desirable feature as the water gets hot.

What I claim as new and desire to secure 75 by Letters Patent is:—

An electric water heating unit, comprising, in combination an outer metallic shell, a carbon shell, open at the bottom, within said metallic shell, non-conducting spacing 80 rings separating said shells and leaving an annular chamber between them, said metallic shell having openings in its side walls connecting said annular chamber with the outer space, and said carbon shell having 85 openings in its side walls connecting said annular chamber with the inner space, an inner carbon shell, open at the bottom, within said first named carbon shell, said inner shell having openings in its side walls connecting the chamber around it with the inner space, non-conducting spacing rings separating said carbon shells and leaving an 90 annular chamber between them, and a combined cap and handle attached to said metallic shell at the upper end thereof, said carbon shells constituting the termini of an 95 electric circuit.

In testimony that I have invented and claim the foregoing, I have hereto set my hand in the presence of two witnesses, this 8th day of December, 1919.

RICHARD M. STEPHENS.
